US00D613337S

(12) **United States Design Patent**
Pearson

(10) **Patent No.:** **US D613,337 S**
(45) **Date of Patent:** **** Apr. 6, 2010**

(54) **CLIP PEN**

(75) Inventor: **Arthur Scott Pearson**, Upland, CA
(US)

(73) Assignee: **Sweda Company, LLC**, City of Industry

(**) Term: **14 Years**

(21) Appl. No.: **29/308,027**

(22) Filed: **May 22, 2008**

(51) **LOC (9) Cl.** **19-06**

(52) **U.S. Cl.** **D19/50**

(58) **Field of Classification Search** **D19/35, D19/36, 41, 42, 43, 44, 45, 46, 47, 48, 49, D19/50, 51, 54, 55, 56, 57; 24/11 F, 11 P, 24/11 R; 401/6, 52, 99, 100, 104, 105, 106, 401/107, 108, 109, 192, 195, 243, 244, 245, 401/246, 247; 362/118**

See application file for complete search history.
